UNITED STATES PATENT OFFICE.

LOUIS TAMIS, OF NEW YORK, N. Y., ASSIGNOR TO SCHANFEIN & TAMIS, OF NEW YORK, N. Y., A FIRM COMPOSED OF BERNARD SCHANFEIN AND LOUIS TAMIS.

VANITY CASE.

Application filed May 27, 1922. Serial No. 564,147.

To all whom it may concern:

Be it known that I, LOUIS TAMIS, a citizen of the United States, and a resident of New York, borough of Manhattan, in the county 5 of New York and State of New York, have made and invented certain new and useful Improvements in Vanity Cases, of which the following is a specification.

My invention relates to a vanity case or 10 toilet article and has for its object to provide an article of this character which may be used as a powder and puff case, a hand mirror, and a lip stick or rouge holder.

A further object is to provide a vanity 15 case which is of simple and compact construction and designed so that it may be readily carried in the pocketbook or purse and will contain all of the necessary articles and appurtenances for enhancing, improving, or making up the complexion and appearance of the user.

A further object is to provide a toilet article which is of neat, attractive and pleasing appearance and ornamental design, and, 20 being provided with a folding handle and made of precious metal, will form a most desirable accessory to a lady's purse or handbag and may be conveniently carried and thus render readily available at all 25 times a novel as well as thoroughly practical hand mirror, powder and puff case, and lip stick.

With the foregoing and other objects in view, my invention consists in the triplex 30 vanity case illustrated in the accompanying drawing and hereinafter described and claimed, and in such variations and modifications thereof as will be obvious to those skilled in the art to which my invention 35 relates, it being understood that changes may be made within the scope of what is claimed without departing from the spirit thereof.

The preferred embodiment of my invention 40 is disclosed in the accompanying drawing, wherein:

Figure 1 is a view in front elevation of my improved vanity case being used as a hand mirror;

50 Figure 2 is a similar view with the mirror portion turned back or open, rendering the puff and powder accessible, the handle being illustrated in section;

55 Figure 3 is a view in section taken on the line 3-3 of Figure 2;

Figure 4 is a view in side elevation of my improved vanity case illustrating the handle folded back against the powder and puff box, whereby the entire article will occupy but little space and may be conveniently carried;

Figure 5 is a view in side elevation showing the vanity case with a handle partially open and serving to support the mirror upon a flat surface;

Figure 6 is a detail view of the lip stick holder as withdrawn from the hollow foldable handle.

Referring specifically to the several views, wherein similar reference numerals designate corresponding parts throughout, my novel vanity case or toilet article comprises a powder and puff box 10, the same being preferably formed of some fanciful outline, such as the octagonal form illustrated 75 in the drawing. The powder and puff box is composed of a rear wall 11 and side walls 12, there being a suitable lid 13 hinged to the side wall and containing the externally visible mirror 14. The hinged lid 13 is preferably provided with the finger-engaging projection 15 and with the small catch 16, the latter being adapted to engage a corresponding projection 17 formed in the side wall of the powder and puff box, so that the hinged 80 lid will snap closed and will stay in such position. The space between the back of the mirror 14 and the rear wall 11 is adapted to house suitable powder and a powder puff (not shown), the same being rendered 85 accessible by opening the lid 13.

Hinged to the lower edge of the powder box, that is, to the edge remote from the hinging of the lid 13, is the handle 18, the hinge 19 being also located adjacent the back wall 11, so that the handle when not in use may be folded up against the back wall, as illustrated in Figure 4, or may be partially folded and thus act as a support and hold the mirror in a slightly inclined position upon a supporting surface, as illustrated in Figure 5.

The hinged handle 18 is provided at its upper extremity with the projection or latch 18' which is adapted to fit within and engage the side walls of the opening 18", so that the handle when unfolded or moved into the position illustrated in Figures 1 and 2 will snap into place and remain so positioned until it is again desired to fold the 110

handle back against the powder and puff box.

- The handle 18 is hollow and open at its lower extremity and into which fits the lip 5 stick or rouge holder 20. This holder is illustrated in detail in Figure 6 and comprises the base 21, the tube 22, and the sliding cup 23. The sliding cup is provided with the finger-engageable knob 24 which 10 travels within the slot 25 cut or formed in the tube 22, so that as the rouge is used the cup holding the same may be moved upwardly and a further amount of the rouge thus exposed.
- 15 From the foregoing it will be apparent that my improved triplex vanity case may be used for a variety of purposes and will be neat and attractive in appearance, may be folded so as to occupy but little space, 20 and thus readily carried in a pocketbook or purse, and being preferably formed of precious metal or suitably plated material, will possess a highly pleasing appearance and thus form a most desirable article.

Having thus described and explained my 25 invention, I claim and desire to secure by Letters Patent:

An article of the class described comprising a relatively flat box of polygonal outline, a hinged lid therefor with an externally visible mirror carried thereby, a handle hingedly secured to the rear edge of said box and at approximately the center of one of the sides thereof, said handle folded against the rear wall of the box and adapted to support the box upon one of the flat sides thereof, a fastener adapted to hold said handle in an extended position, and a lip stick holder detachably secured within said handle. 30 35 40

Signed at New York, borough of Manhattan, in the county of New York and State of New York, this 16 day of May A. D. 1922.

LOUIS TAMIS.
